SURGICAL INSTRUMENT

Original Filed Feb. 29, 1928 2 Sheets-Sheet 2

UNITED STATES PATENT OFFICE

WARD I. HUBER, OF CLEVELAND, OHIO, ASSIGNOR TO W. I. HUBER, INC., OF CLEVELAND, OHIO, A CORPORATION OF OHIO

SURGICAL INSTRUMENT

Application filed February 29, 1928, Serial No. 258,047. Renewed January 2, 1930.

The present invention is an improvement in surgical instruments, and more particularly in snares for removing tonsils, tumors, and so forth, by avulsion. In such operations, it is highly desirable to have an instrument which may be conveniently manipulated and controlled, and which will permit a repetition of operations with expedition and dispatch. The present instrument is so designed and constructed that the operator may manipulate and control it with one hand, and also effect an interchange of snares and snare operating means in a rapid and convenient way while the main operating part of the instrument is held in one hand. The operating mechanism is also arranged to permit the snare to be drawn to smaller dimensions by a step by step or ratchet movement. The wire snare is in itself removable from the snare holding and operating means, but as mounted and attached the snare and its immediate connecting and operating member may be sterilized and handled together and also easily removed from and connected with the operating jaws of the instrument. The instrument also embodies other novel and useful features of construction as herein-after shown and described in detail and more concisely pointed out in the claims.

In the accompanying drawings, Fig. 1 is a side elevation of a wire snare and its mounting on a reduced scale, and Fig. 2 is a side elevation of the pivoted levers or main operating part of the instrument with which the snare mounting is detachably connected. Fig. 3 is an end elevation of the parts shown in Fig. 2. Fig. 4 is a side view of the snare and lever parts of the instrument partly connected, and Fig. 5 a similar view with said parts completely connected and latched as in use. Fig. 6 is an enlarged side elevation of the rotatable holder and bearing member carrying the operating pawl and latch for the ratchet bar, and Fig. 7 is an enlarged side view of the forked and pivoted levers with all its detachable parts removed therefrom. Fig. 8 is a side view of a wire loop or snare unhooked, and Fig. 9 is a top view of the snare tube which contains the ratchet rod to which the wire loop or snare may be hooked.

when the parts are assembled as shown. Fig. 10 is a top view of the instrument with all its working parts assembled, and Fig. 11 is a sectional view horizontally of the same parts on line 11—11 of Fig. 12. Fig. 12 is a vertical section and side view of the instrument, and Fig. 13 a cross section of the snare tube on line 13—13 of Fig. 12. Fig. 14 is a sectional view of a part of the instrument on line 14—14 of Fig. 12, but greatly enlarged when compared therewith. Fig. 15 is an elevation on a corresponding scale of the bearing member which carries the operating pawl and latch for the ratchet bar.

The instrument comprises two levers 2 and 3 which are pivotally connected and have spreading or diverging arms or handles 4 and 5 adapted to be gripped and pressed toward each other by hand against the counter pressure of a spring 6 of any suitable kind interposed between the arms. The upper end of each lever is bifurcated, and these bifurcated ends are normally pressed together or held in contact by spring 6 but caused to separate on an arc when the handles are gripped and compressed by the operator. The arc movement of the levers is utilized to draw a wire loop or snare 7 into the open reduced end of a tube 8 when this tube is seated within and rotatably connected with the bifurcated end of lever 2, and the second lever 3 is connected to a draw member 9 for the loop or snare. A single opening movement of the levers reduces the size of the loop or snare materially, but the loop may be drawn to increasingly smaller dimensions by a ratchet action until the snared material or piece is torn off, cut or severed. The ratchet movement is effected by a spring-pressed detent or pawl 10 which engages a series of beveled teeth 11 on one side of draw member 9. As shown this member is in the form of a round rod or bar having a longitudinal groove 12 in its side into which a pin 14 projects, see Fig. 11. The pin prevents the rod or member 9 from turning within tube 8 while the groove permits the member to slide freely within the tube with the teeth 11 always aligned with the pawl or detent 10. Draw member 9 is reduced in diameter in part and the end

thereof flattened and perforated to permit the hooked extremities 15 of the wire snare or loop 7 to be readily connected therewith when said flat perforated end protrudes from the reduced open end of tube 8, see Figs. 8 and 9. The opposite end of draw member 9 is provided with an enlargement or head 16 to permit the fingers to grasp and slide the draw member back and forth in tube 8, and the pawl or detent and the ratchet teeth are so arranged that the draw member may be pulled outwardly by hand whenever such an operation is expedient or desired. Thus, after attaching the wire loop to the perforated end of the draw member the hooked extremities of the loop may be drawn into the open end of the tube and the loop or snare held against displacement by the frictional contact of the hooked ends with the inner wall of the tube. The tube and draw member, together with the wire loop or snare, may be handled as a separate unit, being readily disconnectible from the levers as hereinafter explained. Accordingly any desired number of such snare units may be provided for the use of the operator, who may easily disconnect each unit from the levers after use and replace it very quickly with another to carry on or complete the surgical operation. Thus, the snare tube has an enlarged base part 17 with flat sides adapted to occupy the space between the bifurcated ends of lever 2, the divided portions 18—18 of which are each formed with a circular opening 19 having a narrowed or flaring entrance 20 at its top. Base part 17 embodies a pair of oppositely extending lugs or trunnions 21 which are flattened or of oblong shape to pass freely through the entrances 20 when the tube is tilted at an acute angle in respect to lever 2 as shown in Figs. 1, 2, and 4, and when the said trunnions are seated within the circular openings 19 the snare tube is pivotally supported and may be turned to a fixed operating position at right angles to lever 2 as shown in Fig. 5. In this right-angled position of the parts the oblong trunnions 21 are locked within the circular openings 19, and the toothed rod or bar 9 rests within an open channel 22 horizontally in the top of a cylindrical bearing member 23 carried by the bifurcated end of the second lever 3. In swinging the snare tube 8 and draw member 9 from an inclined to a horizontal position the said member is brought to a rest position within channel 22 and it is automatically locked and held in that position by a spring-pressed latch 24 of arcuate shape which is pivotally secured to bearing member 23, see Figs. 14 and 15. Latch 24 is confined within a vertical slot 25 in one end of bearing member 23 and has an arm 26 extending upwardly at an inclination across the path of swinging movement of the toothed bar or draw member 9 so that when said bar descends it will strike arm 26 and open the

latch to permit the bar to enter and seat itself in the channel. A leaf spring 27 is secured to one flat side of lever 3 and the free end 27' of this spring is bent at right angles and projected through slot 25 into engagement with the arcuate portion of latch 24 to close the latch automatically. The detent or pawl 10 which works with ratchet effect on the teeth 11 of member 9 consists of a flat piece of metal having a beveled inner end adapted to ride over the inclined faces of the teeth when draw member 9 is pulled outwardly by hand, and this pawl is free to slide within an opening extending axially of one of the flat-sided lugs or trunnions 28 on bearing member 23. A rounded enlargement or head 29 on the outer end of the pawl limits its movement inwardly toward the ratchet teeth, and a leaf spring 30 secured to one flat side of lever 3 bears at its free end against head 29 to hold it yieldingly in locking engagement with the teeth. The channeled bearing member 23 is free to rock or rotate within the bifurcated end of lever 3 inasmuch as its flat sided trunnions 28 are rotatably confined within circular openings 31 in the bifurcated portions of said lever. As in the case of lever 2 these circular openings 31 are also provided with narrowed or flared entrances 32 to admit the flat-sided trunnions when presented at the proper angle and to lock the same within the circular openings in the bifurcated ends of lever 3 when partially rotated therein. The channeled bearing member 23 is itself locked in place in the bifurcated end of lever 3 by the bent end 27' of leaf spring 27, but obviously this member may be detached very readily from lever 3 when occasion requires. When connected to lever 3 the channeled member acts as a holder for the ratchet bar or draw member 9 and this holder is free to rotate on its trunnion within limits or sufficiently to permit the two pivotally connected levers 2 and 3 to open and close with an arc movement at their bifurcated ends while the ratchet bar or draw member 9 slides on a straight line and without bind within snare tube 8. Thus in opening and closing the levers the snare tube is constantly held at right angles to a vertical median line between the levers and the operator has complete and perfect control of the instrument at all times and can apply considerable force or power to draw the loop or snare shut while guiding, holding and operating the instrument in one hand only. If the object snared is relatively large and the snare requires repeated ratcheting operations of the instrument to sever the object, the operator need only draw the lever handles together in his hand, relieve the pressure to permit the spring between the handles to open the levers and reset the ratchet mechanism, and then repeat the operation instantly. Having severed the object or fragment snared, he may

press latch 24 open which will cause the snare unit to drop and tilt by gravity to an angle where its trunnions may be slipped free from the bifurcated end of lever 2, and an interchange immediately effected by inserting 5 a second snare unit into the open bifurcated ends of lever 2. Swinging of the snare unit upwardly then locks it to lever 2 and a snap lock of the ratchet member 9 is effected 10 simultaneously with the pawl holder 23 on lever 3, thereby connecting all the working parts of the instrument operatively together for immediate further use.

What I claim, is:

15 1. A surgical instrument, comprising a snare tube containing a draw member for a snare, and a hand device detachably connected with both the tube and draw member and in clutch engagement with said 20 draw member for imparting relative movement to said tube and draw member.

2. A surgical instrument, comprising a pair of pivotally connected levers, a snare tube connected pivotally and detachably to one 25 of said levers, a member for drawing a snare into said tube adapted to swing into an operating position opposite the second lever, means supported by said second lever to hold said draw member in its operating position 30 and a clutch engageable with said draw member.

3. A surgical instrument, comprising a snare tube containing a member for drawing a snare thereinto, and a pair of pivotally 35 connected levers, one of which is adapted to be connected detachably to said tube and the other having a latch to connect said draw member thereto.

4. A surgical instrument, comprising a 40 pair of pivotally connected levers, a snare tube connected pivotally and detachably to one of said levers, an element extending through said tube for drawing a snare thereinto, a bearing member for said element rotatably supported by the second lever, including means for locking said element within said bearing member, and means carried by said bearing member for clutching and shifting said element longitudinally in the 45 tube upon imparting an opening movement to said levers.

5. A surgical instrument, comprising a pair of pivoted levers, a snare tube having a snare drawing element extending therefrom and provided with a pivotal connection with one of said levers to permit the tube to swing to a horizontal position, and means upon the second lever 55 adapted to effect a disconnectible operating connection for said snare drawing element when said tube is swung to a horizontal position.

6. A surgical instrument, comprising a 60 pair of pivoted levers, a snare tube pivotally connected to one of said levers, a ratchet bar

extending through said tube for drawing a snare thereinto, a holding member rotatably secured to the second lever adapted to receive said element, and a pawl carried by said member for engaging said ratchet bar.

7. A surgical instrument, comprising a pair of relatively movable members, a snare tube pivotally connected to one of said members and detachable therefrom by turning in said pivot, said tube having a shiftable element therein adapted to draw a snare into one end of said tube, and ratchet mechanism connected to the second member adapted to engage and shift said element.

8. A surgical instrument, comprising a pair of bifurcated levers, a snare tube detachably connected to the bifurcations of one lever, a slideable element for drawing a snare into one end of said tube, and clutch means mounted within the bifurcated parts of the 85 second lever and engageable with said element.

9. A surgical instrument, comprising two pivotally connected levers, each lever having a bifurcated end, a snare tube having trunnions adapted to be connected detachably and rotatably to the bifurcated end of one lever, a draw member slidably confined within said tube, a snare detachably connected with one end of said draw member, a bearing and holding member for said draw member having trunnions rotatably connected with the bifurcated end of the second lever, a latch to hold said draw member within said bearing member, and a clutch for said draw member carried by said bearing member.

In testimony whereof I affix my signature.
WARD I. HUBER.
